UNITED STATES PATENT OFFICE.

DAVID S. WILLIAMS, OF PHILADELPHIA, PENNSYLVANIA, ASSIGNOR TO HIMSELF AND JOSEPH A. VINCENT, OF SAME PLACE.

HYDROCARBON INCANDESCENT LAMP.

SPECIFICATION forming part of Letters Patent No. 637,952, dated November 28, 1899.

Application filed October 28, 1898. Serial No. 694,766. (No model.)

To all whom it may concern:

Be it known that I, DAVID S. WILLIAMS, a citizen of the United States of America, and a resident of 903 Walnut street, in the city 5 and county of Philadelphia, State of Pennsylvania, have invented certain new and useful Improvements in Hydrocarbon Incandescent Lamps, of which the following is a specification.

10 My invention relates to new and useful improvements in hydrocarbon-lamps especially adapted to the use of high test hydrocarbon oils, the principal features of my invention being the construction and arrangement of 15 the vaporizing-tube whereby the greatest possible amount of heat is brought in contact with the tube, so as to thoroughly vaporize and superheat the vapor before it enters the burner, and the construction of the regulating-valves and means for regulating the flow 20 of vapor from the vaporizing-tube, thereby dispensing with joints, glands, or stuffing-boxes and preventing the escape of vapor, which has been found to be extremely objectionable in other lamps on account of the disagreeable odor emitted from burners wherein 25 glands or stuffing-boxes are used.

The invention also consists in various other indispensable details of construction, which 30 will be more fully set out hereinafter.

Referring to the accompanying drawings, Figure 1 illustrates a plan view of a high-test hydrocarbon-oil lamp constructed in accordance with my invention. Fig. 2 illustrates a 35 side elevation of the same. Fig. 3 illustrates an enlarged vertical section of the lamp with the upper part of the vaporizing-tube broken away. Fig. 4 illustrates a vertical section of a portion of the expansion-tube, showing the 40 needle-valve fixed and inserted from the outside, the joint being made by a fireproof-fiber washer. Fig. 5 illustrates a sectional plan view on the line 5 5 of Fig. 3. Fig. 6 illustrates a sectional plan view on the line 6 6 of 45 Fig. 3. Fig. 7 is a plan view of the coupling, which is provided with a washer of non-conducting material for the purpose of preventing an escape of heat from the lamp, which would otherwise occur through the medium 50 of the metallic connections. Fig. 8 is a side elevation of a double type of burner provided

with a hood for the purpose of concentrating the heat upon the top of the vaporizing-tube. Fig. 9 is a front elevation of the type of burner illustrated in Fig. 8. Fig. 10 is a sectional plan view on the line 10 10 of Fig. 9. Fig. 11 is a plan view of the hood, which is mounted upon the top of the vaporizing-tube. Fig. 12 is a vertical section of the hood, showing the manner in which the same is secured to the 60 vaporizing-tube. Fig. 13 is a section on the line 13 13 of Fig. 11; and Fig. 14 is a vertical section similar to Fig. 12 of a modified form of hood and vaporizing-tube, the latter being in two parts, each of which is adapted to be 65 threaded to an opening in the hood.

Referring to the reference-letters of the drawings, A represents the body of the burner, provided at the top with a burner-head A' and at the bottom with an expansion-tube A². 70 Mounted directly above the burner-head is a vaporizing-tube B, made in the form of a loop, the members of which are detachably secured to the opposite sides of the burner-head A' and are held in position by set-screws b and b'. The arm A³ of the expansion-tube A² is provided with a threaded valve-stem D, which latter is provided with a detachable needle D', held in position by a clamp D², which admits of the needles being removed 80 and replaced when bent or otherwise injured by careless usage. Below the expansion-tube and between the same and the supporting-bracket F, I find it desirable to place a coupling G, which is formed of two parts g and 85 g', fastened to a section g², which is a poor conductor of heat, and by this means the heat generated by the burners is prevented from being carried off by the bracket F.

For the purpose of heating the vaporizing-tube prior to starting the flame in the burner I use a small quantity of alcohol, which is placed in the cup H, the same being formed upon or united to the burner a short distance below the burner-head. The cup H is provided with arms h, which extend upwardly and terminate in prongs h', which form supports for the globe or chimney I, which may be of any desired shape or size.

In Figs. 4 and 9 of the drawings I have illustrated a modification of my burner in which the needle-valve D is stationary within the

- expansion-tube, while the burner-head A⁴ is separated from and arranged to move upon the lower portion A⁵ of the burner by means of a nut A⁶, by the adjustment of which the vaporizing-tube B, which is carried by the burner-head, is raised or lowered and the discharge end of said vaporizing-tube is brought into contact with the needle-valve to open and close the orifice in the nozzle A⁷.
- 10 Where two or more burner-heads are employed, as shown in Figs. 9 and 10 of the drawings, I find it desirable to use a hood J over the top of the vaporizing-tube for the purpose of concentrating the heat from the burners. Arranged near the center thereof are openings j, through which the products of combustion escape. The hood J is secured to the vaporizing-tube B by a clamp J'; but, if desired, a curved tube J² may be formed in
- 15 said hood, as shown in Fig. 14, in which case the two ends of the vaporizing-tube will be threaded to the openings.
- 20 I have shown in dotted lines in Fig. 9 a modified form of device for adjusting and regulating the flow of vapor from the vaporizing-tube. Formed on the lower part F⁵ of the burner is a projection f⁶, threaded to receive a stem f⁷, which has a reduced end f⁸, adapted to a projection f⁹, which latter is secured to or formed
- 25 upon the upper or movable portion of the burner carrying the vaporizing-tube.
- 30 Having described my invention, what I claim, and desire to secure by Letters Patent, is—

- 35 1. A hydrocarbon incandescent lamp, comprising a burner-head, a vaporizing-tube in the form of a loop, the members of which are removably secured to the burner-head on opposite sides thereof, an expansion-tube provided with an opening for the ingress of air, and with a needle-valve adapted to the discharge end of the vaporizing-tube and means as shown for adjusting the burner-head and vaporizing-tube upon the expansion-tube so
- 40 as to regulate the flow of vapor from the vaporizing-tube.

- 45 2. A hydrocarbon incandescent lamp comprising an expansion-tube, a needle-valve secured within the tube, a burner-head mounted upon the expansion-tube, and free to move vertically thereon, a vaporizing-tube in the form of a loop, the members of which are detachably secured to the burner-head, one member being provided with an oil-supply pipe and the other with a discharge-nozzle adapted to engage the needle-valve, and an adjusting device to regulate the position of the burner-head with respect to the expansion-tube.

- 50 60 65 3. A hydrocarbon-lamp, comprising a vertically-adjustable burner-head, a detachable U-shaped vaporizing-tube, the members of which are secured upon opposite sides of the burner-head, an expansion-tube arranged below the burner-head, having an upwardly-turned end adapted to the discharge end of the vaporizing-tube, a needle-valve secured

within the expansion-tube, engaging the discharge end of the vaporizing-tube and means as shown for adjusting the burner-head upon the expansion-tube.

4. A hydrocarbon-lamp comprising a burner-head, a vaporizing-tube in the form of a loop, the members of which are removably secured to the burner-head, one member being provided with an oil-supply pipe, the other having a discharge-nozzle, an alcohol-cup secured below the burner-head, a globe or chimney surrounding the burner-head and vaporizing-tube, an expansion-tube below the burner-head, means as shown for adjusting the vaporizing-tube and burner-head with respect to the expansion-tube, and a detachable needle-valve located within the expansion-tube and adapted to the nozzle of the vaporizing-tube.

5. A hydrocarbon incandescent lamp comprising a burner-head, an inverted-U-shaped vaporizing-tube, the members of which are detachably secured to the opposite sides thereof, one of said members being provided with an oil-supply pipe while the other is provided with a vapor-discharge nozzle, a globe or chimney mounted upon the burner-head, an alcohol-cup arranged below the burner-head, a U-shaped expansion-tube one member of which is adapted to the discharge end of the vaporizing-tube, a needle-valve secured within said member of the expansion-tube, and an adjusting-nut interposed between the burner-head and the other member of the expansion-tube for adjusting the vaporizer with respect to the valve, substantially as and for the purpose set forth.

6. A hydrocarbon incandescent lamp comprising a burner-head, an inverted-U-shaped vaporizing-tube, the members of which are detachably secured to projections upon the opposite sides thereof, one of said members being provided with an oil-supply pipe, while the other is provided with a vapor-discharge nozzle, a hood mounted upon the top of the vaporizing-tube, a globe or chimney mounted upon the burner, an alcohol-cup arranged below the burner-head, a U-shaped expansion-tube, one member of which is adapted to the discharge end of the vaporizing-tube, a needle-valve secured within said member of the expansion-tube and an adjusting device interposed between the burner-head and the other member of the expansion-tube for adjusting the vaporizer with respect to the valve, substantially as specified.

7. A hydrocarbon-lamp comprising a burner-head, a vaporizer connected with an oil-supply and having a discharge end, an expansion-chamber communicating with the burner having an inlet-opening adapted to the discharge end of the vaporizer, a needle-valve engaging the discharge end of the vaporizer, and an adjusting device for moving the vaporizer longitudinally of the needle-valve.

8. A hydrocarbon-lamp, an expansion-chamber, a needle-valve fixedly connected thereto,

- 5 a burner-head communicating with the expansion-chamber, a vaporizer fixedly connected with the burner-head and connected with an oil-supply, and having a discharge end adapted to the inlet-opening of the expansion-chamber and engaging the needle-valve, and an adjusting device for moving the burner-head and vaporizer with respect to the expansion-chamber and needle-valve.
- 10 9. A hydrocarbon incandescent burner comprising a burner-head, a vaporizer extending above the same, an expansion-tube communicating with the burner-head having a free end provided with a needle-valve, and means for adjusting the vaporizer with respect to said needle-valve.
- 15

10. A hydrocarbon incandescent lamp comprising a burner-head provided with an incandescent mantle, a U-shaped expansion tube or chamber communicating with the burner, a vaporizer extending directly over the mantle and having a downwardly depending discharge end adapted to the upwardly-extending inlet end of the expansion-tube, and a valve for regulating the flow of vapor from the discharge end of the vaporizing-tube.

Signed by me this 24th day of October, 1898.

DAVID S. WILLIAMS.
